Specification for Design.

Patented May 5, 1914.

Application filed March 2, 1914. Serial No. 822,067. Term of patent 7 years.

To all whom it may concern:

Be it known that I, ARTHUR G. KIMBALL, a citizen of the United States, residing at New Britain, Hartford county, Connecticut, have invented a new, original, and ornamental Design for Hot-Water Bottles, of which the following is a specification, reference being had to the accompanying drawing, forming a part thereof, in which—

Figure 1 is a front elevation of the con-

cave face of the bottle. Fig. 2 is an edge elevation of the bottle. Fig. 3 is a cross section through the center.

I claim:

The ornamental design for a hot water bottle, as shown.
